US00D561728S

(12) **United States Design Patent** (10) **Patent No.:** **US D561,728 S**
Kim et al. (45) **Date of Patent:** **** Feb. 12, 2008**

(54) **PORTABLE PHONE**

(75) Inventors: **Young-Sae Kim**, Palo Alto, CA (US);
Chi-Young Ahn, Seoul (KR);
Young-Ju Yeo, Seoul (KR);
Chang-Hwan Hwang, Goyang-Si (KR)

(73) Assignee: **Samsung Electronics Co., Ltd.**,
Suwon-Si (KR)

(**) Term: **14 Years**

(21) Appl. No.: **29/274,719**

(22) Filed: **May 17, 2007**

(30) **Foreign Application Priority Data**

Dec. 14, 2006 (KR) 30-2006-0049758

(51) **LOC (8) Cl.** **14-03**

(52) **U.S. Cl.** **D14/138**

(58) **Field of Classification Search** D14/496,
D14/138, 341-347; 455/575.3, 575.1; D21/517,
D21/329, 333

(57) **CLAIM**

The ornamental design for a portable phone, as shown and described.

DESCRIPTION

FIG. 1 is a perspective view of a portable phone;
FIG. 2 is a front view of the portable phone of FIG. 1;
FIG. 3 is a rear view of the portable phone of FIG. 1;
FIG. 4 is a left-side view of the portable phone of FIG. 1;
FIG. 5 is a right-side view of the portable phone of FIG. 1;
FIG. 6 is a top plan view of the portable phone of FIG. 1;
FIG. 7 is a bottom plan view of the portable phone of FIG. 1;
FIG. 8 is a front open view of the portable phone of FIG. 1;
and,
FIG. 9 is an opened right side view of the portable phone of FIG. 1.
